UNITED STATES PATENT OFFICE.

LE ROY DEVERS AND CLARENCE E. DUNN, OF DAYTON, OHIO.

SAFETY-VALVE.

SPECIFICATION forming part of Letters Patent No. 745,002, dated November 24, 1903.

Application filed March 21, 1903. Serial No. 148,947. (No model.)

To all whom it may concern:

Be it known that we, LE ROY DEVERS and CLARENCE E. DUNN, citizens of the United States, residing at Dayton, in the county of 5 Montgomery and State of Ohio, have invented certain new and useful Improvements in Safety-Valves; and we do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention comprises a safety-valve or cut-off for natural and artificial gases and possesses the new and useful features hereinafter described and claimed.

The object of the invention is to provide a 20 cut-off or safety device which is absolutely and at all times reliable in its operation.

Preceding a detail description of the invention reference is made to the accompanying drawings, of which—

25 Figure 1 is an elevation of our improved safety-valve. Fig. 2 is a vertical section.

In a detail description of the invention similar reference characters indicate corresponding parts.

30 A designates a union of special construction, the ends of which are tapped to receive distributing-pipes A'. The said union has a channel B through its longitudinal center, which communicates with the distributing-pipes and which is intersected by a conical-shaped valve-seat D, that extends entirely through the body of the union. The upper portion of the said union terminates in a suitable offset C, through which the said valve-seat extends and the upper surface of which is flat in order to properly receive the lower edge of a diaphragm G around the valve-seat. The said diaphragm consists of a series of bellows folds which inflate and collapse according to the pressure of the gas exerted on the interior thereof. The lower end of this diaphragm is secured to the upper flat surface of the offset C by means of a suitable washer H, so that the lower extreme end of 45 said folding diaphragm is immovable. The upper end of said folding diaphragm is continuous, as at J, and is secured to the under

side of a disk I, which moves freely within the casing L, said casing being properly secured to the circumference of the offset C and having a cap M.

E designates an elongated valve which fits in the seat D and has its stem F projected upwardly through the center of the folding diaphragm and made secure at its upper end to the disk I by means of a nut K or otherwise. It will be seen that this valve E is of a very slight taper from a vertical line. This is an important feature, for the reason that when the valve is in its seat there will be no possibility of the pressure raising it until after the initial lift has been given it by the set-screw N. The folding diaphragm G, it will therefore be seen, raises the valve E from its seat across the channel B when the flow of 65 gas through the distributing-pipes is normal. At such times the interior of the folding diaphragm is filled with the necessary pressure to maintain the valve from its seat, as shown in Fig. 2. The lower extreme end of the 70 valve-seat D is adapted to receive a lifting-screw N, by means of which the valve is sufficiently raised from its seat to permit of the gas-pressure lifting said valve at such times when the pressure of gas rises to its normal state. In other words, should the pressure of gas suddenly give out or diminish the weight of the valve will cause said valve to drop into the seat with the end thereof in suitable proximity to the end of the lifting-screw N. When the valve is in this position, it is manifest that the channel or passage B will be closed and the gas thus prevented from entering the interior of the folding diaphragm, as well as prevented from passing 75 through the distributing-pipes. When it is desired to sufficiently raise the valve to permit of this normal pressure of the gas having its proper effect to open said valve, the lifting-screw N is turned sufficiently to dislodge 80 the valve E from its seat, and thereby permit a sufficient opening for the gas to enter the interior of the folding diaphragm.

Having described our invention, we claim—

1. In a safety-valve, a union having a gas- 100 passage extending through its longitudinal center, said union having an offset on its upper side through which extends a conical-shaped valve-seat, said valve-seat receiving

at its lower end a lifting-screw, an elongated valve adapted to properly fit said valve-seat and to lie in proximity to said screw when said valve is seated, a folding diaphragm having one end secured to the upper side of said offset, the upper end of said diaphragm being secured to a disk which is freely movable under the expanding and contracting movements of the folding diaphragm, the stem of the valve being connected to said disk so that the folding diaphragm is movable according to the pressure of the gas exerted on the interior thereof, and the valve is controlled and thereby maintained from its seat or permitted to seat, substantially as set forth.

2. In a safety-valve, a union having a longitudinal gas-channel through its center which is intersected by a valve-seat, said union having an offset on its upper side

through which said valve-seat extends, a folding diaphragm secured to said offset around the upper terminal of the valve-seat, so that said valve-seat communicates with the interior of the folding diaphragm, a loose disk to which the upper end of said folding diaphragm is secured, a valve, the stem of said valve being secured to said disk and whereby the valve is caused to move with the expanding and contracting movements of the folding diaphragm, substantially as set forth.

In testimony whereof we affix our signatures in presence of two witnesses.

LE ROY DEVERS.
CLARENCE E. DUNN.
